UNITED STATES PATENT OFFICE.

GEORGE BUERMANN, OF NEWARK, NEW JERSEY, ASSIGNOR TO AUGUST BUERMANN
MANUFACTURING COMPANY, OF NEWARK, NEW JERSEY.

SPUR.

1,135,991.

Specification of Letters Patent.

Patented Apr. 20, 1915.

Application filed May 21, 1913. Serial No. 768,964.

To all whom it may concern:

Be it known that I, GEORGE BUERMANN, a citizen of the United States, and a resident of the city of Newark, county of Essex, and 5 State of New Jersey, have invented certain new and useful Improvements in Spurs, of which the following is a specification.

This invention relates to an improved spur comprising the usual side arms joined 10 at the back so as to form a U-shaped body portion, the back end of the spur being provided with the rowel or any other usual element for prodding the horse, the spur having instep-chains which extend transversely 15 in the form of loops from one side of the spur to the other near the front ends of the arms.

The invention further consists of a spur of this type in which each of the chains is secured 20 at its ends to the arms without any connection with the securing means of the other chain, so that they are independent of one another, and the disposition of the chains can be changed independently, for 25 example, they can be used at different angles without either chain affecting the tension of the other chain.

Another feature of the invention consists in rigid outwardly extending means on the 30 spur arms to which the chains are directly fastened, whereby they are held outward at their secured ends away from the boot so that the chains do not chafe the boot, and there are no connections between the chains 35 to chafe the boot.

The invention is illustrated in the accompanying drawing showing the preferred form of spur, although changes can be made in the details of construction without departing 40 from the invention.

In the drawings Figure 1 is a side view of a spur made according to my present invention. Fig. 2 is a section on line 2—2, in Fig. 1, and Fig. 3 is a front view of one of the 45 ends of the U-shaped body portion.

The spur consists of the body portion 10 which comprises side arms 11 joined at the back as at 12 where the two forwardly extending arms 11 merge into one another, the 50 back 12 having an extension 13 which is forked at its end as is usual in spurs, and is provided with a pin 14 on which rotates the rowel 15.

In the drawings Fig. 1 illustrates one side 55 of the spur, but it will be understood that

the two sides of the spur are substantially identical.

The ends of the arms 11 are provided with upwardly projecting ends 16, the ends 16 having buttons 17 or any similar means 60 for fastening a suitable ankle-strap which is not shown. On the outer sides of the arms 11 and toward their forward ends, preferably at the juncture of the upturned ends 16 and the main portion of the arms 11, are the 65 outwardly extending lugs 18 having holes 19, the lugs 18 being rigidly fixed on the spur, and they are usually made integral therewith. Chains 20 and 21 are arranged transversely beneath the body portion of the 70 spur and are looped with their ends hooked into the holes 19 or otherwise suitably secured to the arms, the chains being secured to the arms 11 independently of each other, and there being no connections between the 75 chains which are movable with respect to the body of the spur. Such movable connecting means when present cause the tension on one chain to be affected by the tension on the other; a relaxation of one chain, 80 for example, will permit a corresponding relaxation of the other. In my present construction, however, the independent fastening of the instep-chains to the spur body by fixed independent means, permits them to be 85 arranged at different angles. In some cases a rider will prefer to have one of the chains arranged under the forward part of his instep, and another chain under the instep close to the heel. This is possible in my 90 form of spur and both of the chains, after being arranged in place, can maintain their tension and if one of the chains should have its tension relaxed for some reason, the tension of the other is not affected through any 95 connecting means, or through any fastening means common to both of them. Some riders prefer to secure one of the chains in the position shown at a in Fig. 1, that is, to run one of the chains in rear of the heel and 100 thus to assist in holding the spur rigidly to the shoe, particularly when the ankle-strap is tightened. My improved structure permits the placing of one of these chains in rear of the heel and the other in front of the 105 heel and when so placed the tension on each of them may be maintained by reason of their being independently secured to the spur body. The lugs 18 which extend outwardly from the outer sides of the arms 11

110

- hold the chains at their ends outside of the arms of the spur, which permits the chains to clear the leather of the boot from the edge of the sole, or extension of the sole under the instep, thus saving this part of the boot from chafing or wear by the chain or its attaching means. It is also to be noted that the outward projection of the lugs 18 prevents the engagement of the chain with the boot leather when the rear chain is put in the position shown at *a*, Fig. 1, since the chain in this position engages the boot at the heel portion only and does not come in contact therewith above the heel.
15. The particular design and form of the spur as shown herein is not essential to its successful use, and details may be altered at will without departing from the scope of the invention as defined in the claims.
20. Having thus described my invention, what I claim is:—
1. A spur comprising a U-shaped body portion comprising arms joined at the rear, the arms of the body portion having rigid outwardly projecting lugs, the lugs having holes at their outer edges, and two chains, each chain having its ends caught in oppositely arranged holes.
  2. A spur comprising a U-shaped body

portion comprising arms joined at the rear, 30 the arms of the body portion having rigid outwardly extending lugs, and two chains, the chains being secured to the outer edges of the lugs so that they are disposed transversely of the spur body portion, each chain 35 being thus capable of independent use on footwear without affecting the tension on the other.

3. A spur comprising a U-shaped body portion, the body portion comprising arms 40 joined and having an extension at the rear and having upwardly projecting ends at the front, the arms at their juncture with the ends being provided with horizontal integral lugs on their outer sides, the lugs having holes therein, and a pair of chains, said chains being substantially parallel and disposed transversely of the spur and being secured independently of each other in the holes of the lugs.

In testimony that I claim the foregoing, I have hereunto set my hand, this 19th day of May, 1913.

GEORGE BUERMANN.
